UNITED STATES PATENT OFFICE

136,317

DESIGN FOR A VOLTAGE REGULATOR

Michael Debrey, East Moline, Ill.

Application June 5, 1943, Serial No. 110,372

Term of patent 14 years

To all whom it may concern:

Be it known that I, Michael Debrey, a citizen of the United States, residing at East Moline, in the county of Rock Island and State of Illinois, have invented a new, original, and ornamental Design for Voltage Regulators, of which the following is a specification, reference being had to the accompanying drawing, forming part thereof.

Figure 1 is a perspective view of a voltage regulator showing my new design.

Figure 2 is a side elevation.

I claim:

The ornamental design for a voltage regulator, as shown.

MICHAEL DEBREY.
